UNITED STATES PATENT OFFICE.

JOSEPH C. FOWLER, OF CHICAGO, ILLINOIS, ASSIGNOR, BY MESNE ASSIGNMENTS, TO
J. RENWICK PRESTON, OF CHICAGO, ILLINOIS.

MACHINE FOR CASTING AND SETTING INDIVIDUAL TYPE.

958,788.

Specification of Letters Patent. Patented May 24, 1910.

Application filed December 30, 1904. Serial No. 239,000.

To all whom it may concern:

Be it known that I, JOSEPH C. FOWLER, a citizen of the United States, residing at Chicago, in the county of Cook and State of Illinois, have invented new and useful Improvements in Machines for Casting and Setting Individual Type, of which the following is a specification.

My invention relates to improvements in machines for automatically casting and setting or composing individual type; and it has for its object to simplify and improve the arrangement and mode of operation of the several and individual constituents of the mechanism, and the production of clear-cut perfected type characters.

With these and other objects, which will be made manifest in the following description, in view, my invention resides in the novel construction, arrangement and mode of operation of the elements of the machine as an entirety; in the several novel elements of the machine, and in the several sub-combinations of elements comprised in the machine.

That which is regarded as new will be set forth in the clauses of claim appended to the description.

In the accompanying drawing I have illustrated, as the statute requires, the best known embodiment of my invention, without, however, intending to restrict the said invention to the details of construction, or otherwise, except as may be set forth in particular clauses of claim, and then for the purpose of those particular clauses only.

In the said drawings:—Figure 1 is a top plan view of the machine. Fig. 2 is an elevation of the left hand end of the machine. Fig. 3 is a similar view of the right hand end. Fig. 4 is a front elevation, the key mechanism being removed. Fig. 5 is a section on line 5—5 of Fig. 4, being a detail of the means for mounting the galley on the galley-regulating screw. Fig. 6 is a rear elevation. Fig. 7 is a vertical section, taken from front to rear, showing the position of the parts when the matrix bars are in initial position in the magazine, the pumps being locked from operation. Fig. 8 is a similar view showing a matrix bar in casting position and a pump operating to effect a cast. Fig. 9 is a plan view illustrating the bank of keys, the matrix-bar magazine and the matrix-bars disposed therein.

Fig. 10 is a sectional elevation of the parts shown in Fig. 9. Fig. 11 is an elevation partly broken away looking at the rear of Fig. 10. Fig. 12 is a view, partly in section and partly in elevation, of the metal-pot, 60 pumps and adjacent elements. Fig. 13 is a sectional elevation of the parts shown in Fig. 12. Fig. 14 is a view, partly in plan and partly in section, of the pot, pumps and pump-locking means. Fig. 15 is a detail 65 elevation looking at the rear of the mold with the nozzle-plate in register with the mold-cells. Fig. 16 is a detail elevation of one of the mold-guides. Fig. 17 is a detail elevation of the mold-yoke and adjacent elements. Fig. 18 is a plan view of the type-ejector. Fig. 19 is a section on the line 19—19 of Fig. 18. Fig. 20 is an elevation of the ejector-finger guide. Fig. 21 is a section on the line 21—21 of Fig. 20. Fig. 22 is a sectional elevation of the type-conveying screw. Fig. 23 is a view, partly in plan and partly in section, of the face plate of the pot. Fig. 24 is an elevation thereof. Fig. 25 is a sectional view on the line 25—25 80 of Fig. 24. Fig. 26 is a sectional view on the line 26—26 of Fig. 24. Fig. 27 is a partial elevation illustrating a portion of the type-conveying screw, the guard and means for locking the screw from rotation. Fig. 28 85 is a sectional view on the line 28—28 of Fig. 27. Fig. 29 is a similar view on the line 29—29 of Fig. 27. Figs. 30 and 31 are views, in edge and side elevation, of the lever for actuating the type-guard. Fig. 32 90 is a plan view of the type-stick and line measuring mechanism. Fig. 33 is a plan view of the line measure. Fig. 34 is an elevation thereof. Fig. 35 is a section on the line 35—35 of Fig. 33. Fig. 36 is an elevation of the scale. Fig. 37 is a sectional plan view illustrating the line-ejecting mechanism and the galley. Fig. 38 is a plan view of a detail of the line-ejecting mechanism. Fig. 39 is an elevation thereof. Fig. 40 is 100 a sectional view taken on the line 40—40 of Fig. 37. Fig. 41 is a section on the line 41—41 of Fig. 37. Fig. 42 is an elevation of the coupling-bolt that connects the line-ejector with the type-ejector for operation 105 of the former by the latter. Fig. 43 is an elevation of the lever for operating said bolt. Figs. 44, 45, 46, 47, 48, 49, 50, 51, and 52 are details of the mold construction. Fig. 53 is an elevation of the mold yoke. Figs. 110

54 and 55 are vertical sectional views of the assembled mold. Fig. 56 is an elevation of the mold-lift cam. Fig. 57 is a section on the line 57—57 of Fig. 56. Fig. 58 is an 5 elevation of the cam for operating the type-ejecting mechanism, and Fig. 59 is a section on the line 59—59 of Fig. 58. Fig. 60 is an 10 elevation of the pump-lift cam. Fig. 61 is a section on the line 61—61 of Fig. 60. Fig. 62 is an elevation of the cam for withdrawing the matrix-bar aliners. Fig. 63 is a section 15 on the line 63—63 of Fig. 62. Fig. 64 is an elevation of the pot-rocking cam, and Fig. 65 is a section on the line 65—65 of Fig. 64.

As will be apparent from an examination of the drawings, my machine embodies a set of matrix-bars bearing character-matrices of any desired font, a mold fashioned for 20 the casting of individual type, means for disposing any desired character-matrix of any matrix-bar in proper position with respect to the mold to secure a cast of such character, means for injecting type-metal 25 into the mold and against the desired character-matrix, means for ejecting the cast type from the mold, and mechanism for transferring said type to and composing it in a composing stick, and means for delivering composed lines from the stick to a 30 galley.

The matrix-bars 1 are arranged in a series in a magazine 2 disposed in front of the mold 3, and are each provided, as is usual, 35 on that edge which faces the mold, with intaglio matrix-characters, and also with a "spacer" or "quad," for casting spaces. The opposite edge of each matrix-bar is provided with a series of recesses 1^c corresponding 40 in position to the character-matrices. The matrix-bars are also provided, at one edge, with a recess 1^d, having coöperation with supports, individual to the several matrix-bars and consisting of arms 4^a of two- 45 armed levers 4 mounted on a rod 5 and capable of rocking thereon. These supports serve, in coöperation with the recesses 1^d to maintain the matrix-bars in stored or inactive position in the matrix-magazine. 50 The other arm 4^b of the levers 4, are disposed in the lines of movement of a series of trip-slides 6, the active strokes of which rock the levers to draw the supports 4^a out of engagement with the recesses 1^d, permitting the matrix-bars to drop in the magazine by gravity. The said trip-slides are 55 operated by key mechanism, the key-levers 7 of which are operatively arranged with relation thereto. As shown, this relation is 60 a loose one, the levers being provided with studs 7^a disposed in the sockets 6^a in the trip-slides and adapted when the keys 7^b are depressed, to engage one wall of the sockets 6^a to propel the slides, trip the matrix-bars and 65 permit the latter to drop. Upon the return

of the keys, after depression, the trip-slides are withdrawn by means of springs 6^b and are in position for further operation. The degree of fall or drop of the matrix-bars is governed in a manner to present any desired matrix-character to the mold. This is accomplished by several vertical series of stops 8, each vertical series corresponding in 70 number to the number of character-matrices and quads with which the related matrix-bar is provided, and the stops of each series are at different levels and each stop of each series is independent of every other stop. The vertical difference between the several 75 stops of each series is equal to the distance from center to center of the character-matrices upon the matrix bars. The stops are supported in any suitable manner, for instance, as shown in the drawing, by means of rods 8^a at the front, the rear ends resting 80 in openings 9^a in a grid 9, and, held against the bottom walls thereof by wires or rods 8^b. Said rods may be in the form of anti-friction rollers, if desired, to lessen the friction and insure ease of movement. The active 85 ends of the stops, in being projected into the matrix-bar magazine, pass through the openings 9^a of the grid 9, whereby they are guided in their movement and maintained in position accurately at the level necessary 90 to stop the matrix-bar at the exact point desired. The stops 8 are actuated at the same time with the trip-slides 6 and by the same mechanism; that is to say, by the key-levers 95 7, the tail-ends of which engage said stops. 100 After their office of stopping the drop of the matrix-bars and supporting them in stopped position, the stops are forced out of the magazine by means of the matrix-bar lifter 17 hereinafter referred to, said stops being 105 beveled off on their under-sides as shown, to permit this action.

The key mechanism consists of a bank of keys comprising a series of keys commensurate with the matrix-bars and the matrix-characters and "spaces" or "quads" thereon, there being a key for each matrix-character, and one for each spacer or quad. 110

To facilitate the insertion of the matrix-bars into the magazine and the removal 115 therefrom as may be required, the front wall 2^a of the magazine is hinged to the frame work of the machine as shown at H so that it may be swung forward to afford an opening and ample working space for these operations. As shown in the drawings, the key-mechanism housing is supported upon the hinged front wall of the magazine. 120

In operation, the keys of the key-mechanism bearing the type-characters which it 125 is desired to cast, are actuated, propelling the appropriate trip-slides into engagement with the arms 4^b of the levers 4, withdrawing the arm 4^a from engagement with the recesses 1^d, in the corresponding matrix-bars 130

and, at the same time, projecting into the magazine those stops in the series appropriate to the given matrix-bars, which correspond in relative position in the series to the matrix-characters in the series of characters on the matrix-bars of which it is desired to take a cast. As many matrix-bars may be dropped for one casting and as many individual types cast in one cycle of operation of the machine as may be found in sequence across the key-board. The selected matrix-bars fall in the magazine until stopped and supported by the projected stops 8, with the proper matrix-character in coincidence with a cell of the mold. Before the casting operation, the matrix-bars are alined and forced tightly against the mold so that there shall be no crevices into which the metal may find its way and form burs on the type. This is accomplished by matrix-bar aliners consisting of a series of spring-impelled plungers 11, one for each matrix-bar. The plungers are set in races 11^a in the front wall of the magazine, and springs 11^b are combined therewith as shown. The plungers are provided with heads arranged to enter those recesses 1^c in the matrix-bars which come opposite the mold, and thus aline the character-matrices 30 with the mold cells. Under the influence of the springs 11^b the plungers press the matrix-bars tightly against the mold. The stems of the plungers pass through openings in a retracting-plate 12 common to all 35 the plungers and are headed at their ends 11^d. After a cast has been completed, the retracting plate is caused to act upon the headed ends of the plungers and withdraw the same from engagement with the matrix-bars, leaving the latter free to be returned 40 to stored, or initial position. The retracting plate is actuated by a rock-shaft 13 with which is connected a crank-arm 13^a connected by means of a link 13^b to a cam A, 45 said link having a stud to work in a cam race α on said cam whereby, at the proper time, the shaft 13 is rocked, causing the retracting-plate to withdraw the plungers as referred to.

50 The mold 3 is shown in detail in Figs. 44 to 52 of the drawing and is of novel construction. It is a built-up one consisting of a bed member 3^a upon which are fitted (by dovetailing or other suitable connection) a series of mold-cell-separating blocks 3^b of hardened steel, made perfectly true and polished by grinding, or in any other suitable manner, and constituting the side walls of the cells, and intervening said 55 blocks are hardened steel cell-bottoms 3^c, having dovetail or other suitable connection with the bed plate. The several blocks 3^b and cell-bottoms 3^c are clamped upon the bed-plate by means of end-clamps 3^d, 60 whereby displacement lengthwise of the bed

is prevented. The several cell bottom pieces vary in width according to the value of the mold cell, whether it be for casting a unit width type-character or a type-character of greater width. The top of the mold 70 consists of a bed 3^e into which are fitted a plurality of sections 3^f, of hardened steel, the connection being by means of dovetailing or otherwise. The beds 3^a and 3^e and the intermediate parts described, are bound together, as an integral structure, by means of bolts 3^g, (Fig. 17), and, as an entity, the mold is secured to a mold-carrier 14 herein-after referred to, by means of bolts 3^h (Fig. 17). By constructing the mold in this manner, the parts thereof with which the molten type-metal comes in contact are not liable to warp and are highly wear-resisting. These are considerations of moment in respect of the practical character of the mold. 85 The reference numeral 15 designates the type metal pot. This pot is pivoted as at 15^a to swing to and away from the mold, its swinging movement being caused by an arm 15^b carrying a stud working in a cam-race 90 15^c on a cam B. Arranged in the pot are a series of pumps corresponding in number with the matrix-bars and the mold-cells. Each pump communicates with a mold cell, as shown in the drawing, by means of a 95 spout 15^d, and each mold cell is in circuit with a pump individual to itself. For economy of space in the pot 15, the pumps are arranged in staggered rows of three, though they may be otherwise arranged. The pump 100 cylinders are designated by 15^e and the pistons by 15^f, and said pumps partake of the movement of the pot. The molten metal in the pot surrounds the pump cylinders and enters said cylinders through suitable passages 15^g, when said passages are uncovered by the pump pistons. The pot is subject to heat from any suitable source to maintain the type-metal in a molten condition. In the drawing is illustrated a type of gas 110 heater 15^h, which need not be described in detail as it constitutes no part of my invention, and any suitable heating means may be utilized. A heating jacket 15^m, into which lead heating conduits 15ⁿ, provided in the 115 metal-pot face-plate 28^b is provided adjacent the delivery ends of the pump spouts to avoid otherwise possible cooling of the metal in its passage through this part of the pot. The pump pistons are guided and work through openings in a plate 15ⁱ, mounted on the metal pot by means of brackets or pedestals 15^j, and when the pot is in casting position are supported and locked from operation, ready to act, when free to do so, to 120 eject metal from the pump-cylinders into the mold by means of spring bolts 15^k mounted and capable of movement in the plate 15ⁱ. The action of these bolts is controlled by the matrix-bars and intermediate bolt- 125 130

sliders, said matrix-bars when in initial, or stored position, holding the spring-bolts, against the tension of their springs, into engagement with sockets or recesses 15° of 5 suitable form, with which the pump pistons are provided, thereby preventing the operation of said pumps. The intermediate bolt-sliders referred to consist of shuttles 15°, arranged in openings in the mold-carrier 14, 10 abutting the spring-bolts 15^k, and having springs the tension of which is opposite but relatively weaker than that of the springs associated with the bolts 15^k. When a matrix-bar drops, as before described, for 15 taking a cast of one of its matrices, the spring-bolts 15^k are free to act to withdraw from the pump-piston-sockets 15^l and permit the piston to be operated. In this action, the end of the corresponding shuttle 15° 20 is projected into the matrix-bar magazine above the matrix. When the matrix-bars are in stored, or initial, position there is no room for movement of the shuttles, and, therefore, the spring-bolts 15^k are held in 25 engagement with the sockets 15^l, preventing operation of the corresponding pump-piston. In this manner, only those pumps appropriate to a dropped matrix-bar and corresponding mold-cell, are capable of operation. This is a decided advantage in 30 that the metal is projected only into the spout leading to the mold-cell of which a cast is to be made, as distinguished from those machines in which the type metal is 35 projected into a common discharge orifice of the pot from a part of which only it is discharged. It has the advantage that only so much metal as is needed is acted upon, eliminating all unnecessary work of the machine and avoiding liability of metal being 40 projected in between the metal pot wall and the cut-off gates of prior constructions, burr-like, which would result in the metal hardening at the discharge mouth of the pot-passages and finally clogging the same. 45

The pump piston-stems are spring actuated, being surrounded in the specific instance shown, by spiral springs 15^p, bearing at one end against bosses 15^q with which the 50 stems are provided, and at the other end against a cross-bar 15^r connecting the upper end of the standards 15^l supported by the metal pot. The pump-cylinders, spouts, pistons, and piston-stems (together with the 55 guides for the latter) and the spring-locking bolts, all partake of the swinging movement of the pot. When the spring-bolts 15^k are arranged for coöperation with sockets 15^l in the piston-stems, said stems are provided 60 with cross-arms 15^z which work in slots in the cross-bar 15^r whereby rotation of said stems is prevented and the sockets will always be in proper line to receive the bolts. If the sockets for the spring-bolts be annular 65 recesses, as may well be, such cross-arms, or their equivalent, will not be required.

The return stroke of the pump pistons is effected from a cam C with which a piston-retractor C' is connected by appropriate intermediates, consisting, as shown, of links 70 C² one end of which is connected with the retractor and the other ends of which are connected to the sleeve C⁴ of a rock-lever C³, mounted on a shaft C⁵ and provided with a stud working against the cam C. The piston-retractor works in slots 15^t in the brackets 15^l and is capable of movement toward and away from the pump-cylinders. Normally it supports the pump pistons out of action, when the metal-pot is rocked away 75 from the mold, the said pistons passing through openings in said piston-retractor and the bosses 15^q resting thereon. When the retracting element is moved toward the pump cylinders by means of the cam C and connections described, those pistons which are free to act by reason of the withdrawal of the spring-locking bolts will, by the force of the piston-propelling-spring accomplish 80 their active, molten-metal-projecting stroke. 85 At the proper time, the said pistons are returned to initial position by the retracting element which is moved away from the pump-cylinders by said cam and intermediate connections. 90

The operation of effecting a cast will now be understood and may be briefly described as follows: The mold being assumed to be in casting position with a matrix-bar or bars 95 properly positioned in front thereof as before described, the metal-pot is swung forward into contact with a nozzle-plate carried by the mold and hereinafter referred to, with the pump spouts establishing communication through said nozzles to the mold-cells. Those of the spring-locking bolts 15^k which are free to do so by the dropping of the corresponding matrix-bars withdraw 100 from engagement with the correlated pump-piston stems, permitting operation of the 105 pumps. The remaining pump-piston-stems are locked from movement by their spring-bolts, as before stated. At this time the cam C and intermediate connections move the piston-retractor toward the pump-cylinders, and the pistons are free to act. The active strokes of the pump-pistons force molten type-metal into the appropriate cell or cells of the mold and against the intaglio character-matrices positioned in front 110 thereof, casting type therefrom, or against a quad or quads to cast spaces. The next step in the sequence of operation of the machine, is the removal of the cast type or 115 types from the mold. For this purpose the mold is carried from casting position to type-ejecting position. The mold 3 is 120 mounted in a carrier 14 which is shown as

a yoke, capable of reciprocating movement in guide-ways 14^a in the frame of the machine. Said carrier is connected to arms of a rock-lever D' having a tubular sleeve D⁵. 5 mounted on a rod D², by means of a link D³. The other arm D⁴ of said rock-lever operates with a cam D on the counter-shaft S. Aside from its reciprocating movement, the mold-carrier is capable of slight movement away from the matrix-bar for the purpose of withdrawing the cameo type characters from the intaglio matrix-characters. One of the guides in which the mold-carrier is arranged, is shown in detail in Fig. 16. 10 15 To permit the mold to be moved to a position tight against the matrix-bar and withdrawn therefrom, the guide-ways are provided with pockets 14^b into which laterally extending studs 14^c with which the mold-carrier is provided, may pass, as shown in full lines in Fig. 15 and from which said studs may be withdrawn, as shown in dotted lines in said figure. When the studs are disposed in the pockets of the guide-ways, the mold 20 25 will be in a position of close relation to the matrix-bars, and when withdrawn therefrom to separate the type-characters from the matrices, the studs will be in dotted line position and in direct line for vertical travel in the mold-carrier guides. When 30 35 the parts are in casting position the mold is connected to the metal pot by means of hooks 14^d carried by the metal pot, which hooks are engaged by projections 14^d with which the mold is provided. When the mold is in casting position, the elements 14^a and 14^c are interlocked, so that when the metal-pot is swung or tilted away from the mold, it takes the latter with it sufficiently 40 45 to separate the type from the matrix. After this movement, the cam D, through the intermediate connections described, or other suitable connections, causes the mold to rise in the guide-ways, from the casting to the type-removing position.

Movably secured to the mold, by means of a screw or pin and elongated slot connection 16^a, (as best shown in Fig. 15), is a nozzle-plate 16 having nozzles 16^a adapted to coincide with the mold-cells when in casting position, and in which a nib of metal remains when the casting operation has been completed, which nib must be separated from the body of the cast type. The nozzle-plate partakes of the movement of the mold in both reciprocatory movements of the latter, but the movement thereof is slightly less than that of the mold, to the end that the nibs may be separated from the body of the type. The movement of the nozzle-plate is limited by suitable stops 50 55 60 65 16^b and 16^c provided in the guide-way in the path of movement of said nozzle-plate. During the rising movement of the mold the

nozzle-plate comes into engagement with the stop 16^b whereby its further movement is prevented, the mold continuing its movement independently of the nozzle-plate, with the result that the nibs referred to are separated from the type-body, and the 65 nozzles in the said plate, which now contains said nibs, are brought into register with a series of passages 16^c through the mold-bed, through which, as hereinafter described, the nibs are ejected. Simultaneously with the ascent of the mold, the matrix-bars are returned from stored, or initial, position in the magazine by means of a lifting device 17, which is itself lifted with the mold-carrier by means of tongs 17^a 70 75 pivotally connected to the mold-carrier and engaging lugs 17^b on the lifting-device 17, the tongs being held in engagement therewith by means of a spring, or equivalent, 17^c. The matrix-lifter moves, together with 80 85 the mold-carrier, a sufficient distance to return the matrix-bars to initial position and the connection thereof with the mold-carrier is then released, the latter, together with the mold, continuing its movement and the lifting-device returning by gravity, to its normal position. The lifter 17 is provided with a piston 17^a working in a dash-pot 17^e, whereby its descent is cushioned. The release of the lifter from the mold-carrier 90 95 is effected by cams 17^f which engage the tail-ends of the tongs, withdrawing the latter from engagement with said lifting-device.

While the remaining operations of the machine are being performed, the operator 100 may, in the manner heretofore set forth, bring another matrix-bar or bars into position for casting, effecting great saving of time as the next cast can be taken immediately upon return to position of the mold, 105 without waiting thereafter the manipulation of the finger-keys and the positioning of the matrix-bars. At the upward limit of movement of the mold-carrier, the mold-cells will be in substantial alinement with 110 type-ejecting mechanism, and the nozzles 16^a and passages 16^c will be in coincidence and in substantial alinement with nib-ejecting mechanism.

By means of an ejector 18, mounted to 115 reciprocate on the machine frame opposite a rail 18^a, the type are ejected from the mold onto said rail, passing through guide-channels 22^c. The ejector is reciprocated by a cam E on the countershaft, with which cam 120 an arm E', connected with the ejector frame, engages; this cam being so positioned on the countershaft that it will operate to cause the active stroke of the ejector when the mold has risen to type-ejecting position. In the 125 preferred, and illustrated, example of ejector, said mechanism consists of a frame 18^b provided with a series of fingers 18^c ar-

ranged in a line to enter and eject the type from the mold-cells, and a series of fingers 18^a arranged in a different plane coincident with the nozzles 16^a, which fingers enter and 5 eject the nibs from the nozzles. 18^k designates a guide block through openings in which the fingers 18^c and 18^d work. The nibs may be permitted to pass down through the open spaces in the machine frame, or may be carried off laterally by a chute, if desired, and 10 may be re-melted for further use. The guide block 18^k is provided with a scraper 18^j, which during the rising movement of the nozzle-plate scrapes any spuds or burs 15 which may have formed on the nibs and spread onto the face of said plates around the nozzles.

During the operation of ejecting the type from the mold, the latter rests against a 20 front support projecting from the rail 18^a, consisting of a series of abutments 22^d separated by spaces 22^e, the latter affording clearances through which the cameo type characters 25 projecting from the mold pass. In order to insure the accurate register of the type-ejecting and nib-ejecting teeth, with the mold-cells and nozzles, the ejector is provided with registering arms 18^c, the noses of which are slightly beveled as shown at 18^f. These arms 30 enter in under the guides 18^g and slightly lift the mold, and bring the cells thereof into horizontal alinement with the ejector-fingers. A pair of pins 18^h slightly longer than the fingers 18^c are arranged on the ejector-frame, and enter register holes 18ⁱ in the mold whereby accurate register of the 35 ejector-fingers and mold cells is established and maintained. After having performed the office of ejection, the ejecting element is 40 retracted by the cam E. After the type is ejected therefrom, the mold is returned to casting position, in the meantime the pot being slightly rocked forward by means of a suitable formation of the pot-operating cam, the face-plate 28^b of the pot being disposed 45 in proper line for the action of a wiper 28 yieldingly carried by a spring 28^c connected with the mold carrier, which wiper sweeps across said face-plate and keeps it clean. 50 When the mold has arrived at the proper level the hook elements carried thereby fit into the hook elements of the pot and said pot is then rocked forward, the studs on the mold-carrier frame entering the pockets in 55 the guides, and, at the same time, the aliners enter the appropriate recesses in the matrix-bars and force the matrix bars tightly, against the front of the mold in which position the parts are in proper relation for 60 casting, and a cast is effected as before described. The type previously ejected onto the rail are then transferred to, and set up, or composed in, a stick 19, by means of a screw-transferrer 20. This screw-transferrer is shown in detail in Fig. 22, and in frac-

tional view in connection with immediately coöperating members in Fig. 27. The screw is provided with a series of grooves 20^a of different width, one or more grooves being of a width to receive unit width type, another to receive two-unit width type and another to receive type of greater unit width. The provision of grooves of different widths is desirable in that they are commensurate with the width of the type and prevent possibility of the latter falling over on their sides which would be a serious objection necessitating the subsequent righting of the type. It is found, in practice, that a groove of a given width may properly take care of type of different width within a limit; that is to say, a groove of width x may properly take care of a single or double unit type; a groove of the width y will take care of type of three or four unit width, and so likewise, 70 with a groove of width z . If desired, however, there may be a special groove for each unit of width of the type. Therefore, I desire it understood that this part of my invention is not restricted to any particular 75 number or width of grooves. The vari-width grooves of the screw-transferrer are so disposed on the screw with reference to the mold-cells and matrix-bars (the mold cells being also of vari-width for the purpose of casting type of different unit width and the characters of different width being disposed on the matrix-bars to correspond thereto) that type of given width will be 80 ejected in front of and enter into a groove 85 of suitable width to take care of the proper transfer of the type to the stick. 90

The type-pushing walls 20^b of the several grooves are cut in lines at right angles to the axis of the screw, whereby the type travel 105 upon the table 18^a with one flat side resting thereon and another flat side against a vertical pusher, rather than on a corner as might occur if the pushing walls of the groove were not vertical. The screw delivers the type into the stick in that sequence in which they were cast, and, therefore, properly composed. When the screw is caused to rotate it will be observed that, unless guarded against, there would be a tendency to, and a probability of, the type passing out of the screw. A guard 21 is provided to prevent this, and it is designed, after ejection of the type, to rise as shown in dotted lines in Fig. 27, and close the gap 110 between the table 18^a and the screw, and constitute a wall along which the heels of the type move in their transference. The guard 115 retires from its active position and the screw comes to rest during the operation of ejecting the type from the mold. The action of the screw is periodic, rotating while the mold returns to casting position and until it returns to ejecting position when its rotation ceases, and it remains at rest while the type 120

are ejected. After the type are ejected, the screw rotates and delivers into the stick all the type under its influence. This periodic operation is governed, in the present example of my invention, in unison with the governing of the guard 21, and preferably by the means illustrated. The guard is movably mounted on the table 18^a by pin and angular slot connection 21^a whereby it has a compound movement, longitudinal and rising and falling.

A lever 22 is pivoted on the right hand mold-carrier-guide adjacent the guard 21. One end of said lever is connected to the guard in a manner that will permit of the compound movement of the latter as hereinbefore referred to, in the present instance the end of said lever fitting in between a pair of pins 22^a secured to the guard. The other end of the lever is in the path of movement of a double cam 22^b carried by the mold-frame, or other part of the mechanism moving with the mold. Just before the mold reaches the limit of its rising movement, the end of the lever 22 is engaged by the upper member of the double cam which causes said lever to rock and shift the guard-plate longitudinally, in which movement said guard will ride down upon the screws by which it is connected to the table, withdrawing the guard from active position and leaving an opening for the passage of the type from the mold into the grooves of the screw. On the reverse movement of the mold in coming to casting position, the lower member of the double cam engages the end of the lever 22 and rocks said lever in the reverse direction causing the guard to rise and close the space between the table and screw as set forth. The type-transfer-screw is provided with a shaft 20^c, driven by a belt and pulley connection 20^a, 20^b, from the main shaft P. Rotation of the screw in a direction the reverse of that designed is prevented by a ratchet 20^c secured to the shaft with which a pawl 20^d carried by a fixed part of the machine, for instance the rail 18^a, engages as shown in Fig. 29. If free to do so, the screw would constantly rotate. This rotation, however, is intermittently stopped while the process of type-ejecting is being performed, the belt 20^a slipping during such time as the screw is locked from rotation. This stoppage is accomplished as follows:—Pivoted to the guard 21 is a spring-pressed latch arm 23, the nose of which is adapted to engage an offset 23^a formed on a boss or ring 20^b on the shaft of the screw, the tendency of the spring 23^b being to force the latch into position to engage said offset. A stop 23^c limits the movement of the latch in one direction. The latch being carried by the guard moves with the latter when the guard rises into action as described, disengaging the offset 23^a, and permitting the screw to rotate. When the

guard is withdrawn from action the latch will move into the path of the offset 23^a and come into engagement with the nose of the latch and further rotation of the screw is thereby prevented.

The type, in being transferred to the stick, push gradually to the left a line measure which, initially, is at the right hand or entrance end of the stick. This line measure, as shown, consists of a plate 19^a, with which is connected a marker-arm 19^b. The plate 19^a is provided with a series of recesses 19^c into any one of which may be inserted a pin 19^d which pin is designed to engage the hereinafter referred to block 24^e. When a maximum length line is to be composed, the pin is located in the right hand recess 19^c and when so inserted will not engage the block 24^e until a later period than it would if it were seated in either of the other recesses. For a short line the pin would be seated in the left hand recess 19^c, and for lines of intermediate length, would be seated in one of the other recesses. The marker-arm 19^b is provided with a pointer 19^e arranged to pass in front of a scale 19^f secured to the front of the rail 18^a. This scale, in the particular design of machine shown, has a range of 212 units for a full length line and the pointer is, initially, at the 212 unit indication and is gradually moved toward the zero mark during the composition of a line. By means thereof the operator will be advised of the state of the line in course of composition and when it is nearly completed will be guided in respect of filling out the line with an additional word, part of a word, or with spaces. The justification of the line will be effected by an operator as is now done with hand composition. If desired, an alarm, such as a bell, may be arranged in connection with the index and pointer to notify the operator when his attention to the conclusion of the line is necessary. When a line has been composed and ejected from the stick into a galley, as next to be described, the line measure is returned to initial position by the operator and is provided with a handle 19^g which may be grasped for this purpose. The line ejecting mechanism illustrated is constructed, arranged and operated as follows:—A plate 24 is mounted to slide on the machine frame across the stick to push the composed line therefrom into the galley. This slide is actuated by type-ejector 18 at the proper times, to wit, when a complete line has been composed, said ejector being provided with an arm 24^a with which a coupling bolt 24^b is caused to coöperate by mechanism actuated by the composed line. The said bolt 24^b is shiftably arranged in a head 24^c to which the line ejector plate is secured. A lever 24^d is pivoted on the machine frame adjacent the stick, one end thereof being connected to the said bolt and

the other end carries a block 24^e which, normally, and under the influence of a bolt-retractor spring 24^f slightly enters the composing space of the stick, the arrangement 5 being such that when sufficient type characters and spaces to complete a line of desired length have been arranged in the stick, said block will be moved, rocking the lever 24^d and projecting the bolt into the path of 10 the arm 24^a, in which position, upon the next forward movement of the type-ejector frame, the line-ejector will be advanced, sweep over the stick and transfer the composed line therefrom into the galley, after 15 which it will be withdrawn by, and together with, the type-ejector mechanism, which engages a fixed abutment 24^g carried by the head 24^c, leaving the stick in condition for receiving a further line of type. When, 20 preparatory to the composition of a new line, the operator draws the line measure to initial position, the spring 24^f retracts the bolt 24^b and through the lever 24^d disposes the block 24^e slightly in the composing space of the 25 stick to be acted upon when the next line of type is completed. The spring 24^f is arranged upon a stud 24^h projecting from an abutment 24ⁱ arranged on the head 24^c, said stud having movement in a lug 24^k carried 30 by the bolt which serves also as an abutment for said spring. Above the line composing space of the stick is arranged a lead magazine 25 having a passage 25^a at its lower end and in which are arranged a number of 35 leads. A means for removing the leads and depositing the same with composed lines of type in the galley to alternate with said lines, is secured to the head 24^c. This means consists of blades 25^b which move in unison 40 with the line-ejecting-plate. On the forward or active stroke, they enter the passage 25^a and carry a lead out of the magazine through said passage, which lead assumes position on top of the line of type that is, 45 at the same time, ejected from the stick by the line-ejecting-blade.

A galley 26 is arranged and moves in a guide 26^a and is mounted upon a screw 26^b, which controls its movement, by means of an 50 arm 26^c. The screw is arranged and supported in brackets 26^d projecting from the guide 26^a. The arm 26^c is provided with a divided nut 26^e that encircles the screw. As shown, this divided nut comprises two 55 hinged sections, a thumb screw for holding the sections together about the screw. The guide 26^a is provided with rails 26^f which project in front of the galley and hold the same in said guide. One of the 60 said rails is adjustable, being connected to the body of the guide by a pin and slot connection 24^g whereby it may be moved toward and away from the stationary rail of the guide to permit the entrance into and 65 withdrawal of the galley from the guide.

The adjustable rail of the guide is held in position of adjustment by a set screw 26^h. By means of this construction, or equivalent, a galley may be removed with facility, and another substituted to receive the composed 70 lines from the galley. When it is desired to compose lines of different length, galleys having like external dimensions, but the line-receiving spaces of which are of different width, may be inserted into the galley-guide. 75 As stated, the movement of the galley is controlled by the screw, rotation of which, in one direction, will cause the galley to move forward in the guide. The screw is rotated automatically, and immediately 80 after the ejection of a line from the stick into the galley, to lower the galley sufficiently to carry the line of type and lead deposited therein slightly below the surface of the composing bed of the stick, so 85 that the galley will be in position to receive another line ejected from the stick. The screw-controlling means consists as shown, of a rack 26ⁱ slidably arranged upon the machine frame and adapted to mesh with a 90 pinion 26^k loosely fitted to rotate upon the upper end of the screw and provided with an arm 26^l in which is mounted a spring-pressed dog 26^m adapted to coöperate with a ratchet 26ⁿ rigidly connected with the 95 screw, whereby, upon rotation of the pinion 26^k in one direction, the ratchet, together with the screw with which it is connected, is rotated. On reverse rotation of the pinion the pawl rides over the teeth of the 100 ratchet without effecting rotation thereof. The rack is actuated by an arm 26° of the line-ejector mechanism which fits in between shoulders 26^p and 26^q of said rack, whereby, 105 on the active stroke of the line-ejecting blade, the rack causes rotation of the pinion 26^k and the arm 26^l connected therewith, a predetermined distance, causing the dog to ratchet over the teeth through a given arc. When the line-ejecting blade is withdrawn, 110 the rack causes reverse rotation of the pinion 26^k and its arm, the dog now acting upon the teeth of the ratchet 26ⁿ and imparting rotation to the screw, sufficient, according to the pitch of the screw, to lower the 115 galley the desired degree. The screw-rotating mechanism is capable of adjustment to cause greater or less rotation of the screw and greater or less movement of the galley to provide the proper degree of movement 120 for type bodies of different depth from top to bottom. This is accomplished by making the lug 26^q adjustable on the rack with relation to the rack-pusher shoulder 26^p. By adjusting this lug forward, or away from, the element 26^p the arm 26°, in the active 125 stroke of the line-ejecting blade, will not act upon the rack until part of the stroke of the line-ejector blade has been accomplished, whereby a lesser throw of the rack 130

in its forward or dog setting stroke, is accomplished, and upon the return or screw-rotating stroke of the rack the action of the arm 26^a upon the shoulder 26^a is postponed, 5 and the active stroke of the rack is correspondingly decreased, resulting in a lesser rotation of the screw and a lesser movement of the galley. The screw is provided with a handle 26^c whereby the screw may be rotated to adjust the galley initially with respect to the composing surface of the stick, it being desirable that, in the beginning, the bottom of the galley shall be very slightly below such surface, to the end that the line 10 of type may be pushed off the stick into the galley without possibility of obstruction, and, at the same time, without possibility of the type becoming in any wise disarranged. When a galley is filled with a composed line 15 of type and leads, it may be readily removed from the galley-guide by loosening the set-screw 26^b, moving the adjustable guide-rail 26^c and opening the nut 26^d when the galley can be withdrawn directly out of the guide 20 and another inserted therein and connected with the screw for operation.

In the event a line shorter than a full length line is to be composed, a line-ejecting plate and lead-pusher blades and lead magazine of corresponding dimensions will be 30 incorporated in the machine.

The front or face walls of the galley and the lead magazine may be of glass *g*, or other transparent material, to enable the 35 operator to view the condition of the type in the former, and the supply of leads in the latter.

The mold is cooled by means of water or other cooling fluid which circulates through 40 pipes *W* and passages *W'* in the mold.

The machine is started on a cycle of operation by the actuation of a starting mechanism, shown as a treadle 27 which connects through an intermediate link and lever 45 27^a with a shipper rod 27^d which operates a clutch arranged on the cam shaft, and consisting of a member 27^c loose upon said shaft and having operative connection by means 50 of a gear 27^e with a gear 27^f on the main or power shaft. The fixed member of the clutch is designated by the reference numeral 27^a. The upper end of the shipper-rod is beveled as at 27^g and is adapted to engage an oppositely beveled recess 27^h 55 formed in a bolt 27ⁱ carried by the fixed member of the clutch and adapted to be projected into a socket 27^k by means of a spring 27^l to connect the two parts of the clutch together whereby the cam shaft is 60 driven from the main or power shaft. When the starting treadle is released, a spring 27^m restores it to normal position, withdrawing the shipping lever from the bolt and allowing the bolt to be withdrawn 65 from the loose member of the clutch by the

spring 27^l, the machine coming to rest after the performance of its cycle of operation. After the operator has positioned a matrix-bar or bars in front of the mold for a cast, he actuates the starting lever which places 70 the cam-shaft in gear with the main, or power, shaft and the machine starts on one cycle of operation during which it accomplishes the casting operation, shifts the mold, ejects type therefrom and conveys the 75 type to the galley, after which the clutch is released and the machine comes to rest until the operator is ready for another cast and sequential operation of the mechanisms.

Having thus described my invention what 80 I claim is:

1. The combination with a mold having cells adapted for casting individual type, of a metal pot, a series of pumps arranged for operation in the pot, a series of matrix bars 85 having character matrices, means for releasing the matrices, and locking means for the pumps governed by the matrices and released instantly upon the release of the matrices.

2. The combination with a mold having cells adapted for casting individual type, of a series of matrix bars, means for selectively presenting individual matrix characters in front of the mold cells, a metal-pot, a series 95 of pumps corresponding in number with said cells and operating in said pot and having independent communication with the mold cells, and locking means for the pumps governed by the matrices and released instantly upon the presentation of a matrix character to a mold cell.

3. The combination with a mold having cells adapted for casting individual type, of a metal-pot, a series of pumps operating in 105 said pot and having independent communication with the mold-cells, a series of matrix-bars having matrices, means for selectively presenting the matrices to the mold, and means governed by the matrix-bars for locking part of said pumps from operation and permitting operation of the remainder thereof.

4. The combination with a mold having cells adapted for casting individual type, of a metal-pot, a series of pumps arranged to operate in said pot and having independent communication with the mold-cells, a series 115 of matrix-bars having matrices, means for selectively presenting said matrices to said mold, and bolts for engaging elements of the pumps, the co-operative relation between said matrix bars, pump elements and bolts being such that when the matrix-bars are in their initial, or stored, position, the pumps 120 are locked from operation, and when the matrix-bars are in type-casting position the pumps are free to operate.

5. The combination with a mold having cells adapted for casting individual type, of 130

5 a metal pot, a series of pumps in the same arranged to operate in said pot and having independent communication with the mold-cells, a series of matrix bars having character matrices, a key mechanism and intermediate mechanism actuated by the key mechanism for selectively presenting a matrix to a mold cell, and means for locking the pumps against operation released immediately by the matrices when presented to the mold cells.

6. The combination with a mold having cells adapted for casting individual type, of a metal-pot, a series of pumps corresponding in number with said cells and arranged for operation in said pot and having independent communication with the mold-cells, a series of matrix-bars having character-matrices, means for locking the pumps against operation governed by the matrices, key mechanism and intermediate connections for presenting the character-matrices to the mold and instantly releasing the locking means to permit of the active stroke of the corresponding pumps, means involving a cam for imparting the active stroke to the pumps, and means for imparting the return stroke of the pumps.

7. The combination with a mold having cells adapted for casting individual type, of a metal-pot, a series of pumps corresponding in number with said cells and arranged for operation in said pot and having independent communication with the mold-cells, a series of matrix-bars having character-matrices, means for locking the pumps against operation governed by the matrices, key mechanism and intermediate connections for presenting the matrix characters to the mold and instantly releasing the locking means to permit of the active stroke of the corresponding pumps, means involving a cam for imparting the active stroke to the pumps, and cam-actuated means for imparting the return stroke of the pumps.

8. The combination with a mold having cells adapted for casting individual type, of a metal-pot, a series of pumps arranged for operation therein and having independent communication with the cells of the mold, means for rocking said pot to and from the mold, a series of matrix-bars having character-matrices, means for supporting the pump-pistons in normal position, means for holding the pumps from operation when the pot is in position away from the mold and for returning said pumps to normal position after operation, means coöoperating with the matrix-bars for locking said pumps from operation when the metal-pot is in operative position with relation to the mold, and means for withdrawing said locking means when a corresponding matrix-bar is presented to the mold.

65 9. The combination with a mold having

cells adapted for casting individual type, of a metal-pot, a series of pumps arranged for operation in said pot, a series of matrix-bars having character-matrices, a series of bolts arranged to engage an element of each of said pumps, a series of shuttles interposed between said bolts and the matrix-bars to hold the bolts in locking engagement with the pump element when the parts are in casting position, and, means for withdrawing the bolts from such engagement when corresponding matrix-bars are presented to the mold.

10. The combination with a mold having mold-cells adapted for casting individual type, of a series of matrix-bars having character-matrices, key mechanism for selectively presenting such matrices to the mold, a rocking metal-pot, a series of pumps arranged for operation in said pot and having independent communication with the mold-cells, means for normally locking said pumps from operation, and means actuated by the key mechanism for permitting the operation of said pumps, means for shifting said mold from casting to ejecting position and means for ejecting type therefrom.

11. The combination with a mold having mold-cells adapted for casting individual type, of a series of matrix-bars having character-matrices, means for presenting such matrices to the mold, a rocking metal-pot, a series of pumps arranged for operation in said pot and having independent communication with the mold-cells, a nozzle-plate interposed between said mold and said pot and having nozzles communicating with the mold-cells and with the several pumps, means for shifting said mold and nozzle-plate from casting to ejecting position and means for ejecting the contents therefrom.

12. The combination with a mold having mold-cells adapted for casting individual type, of a series of matrix-bars having character-matrices, means for presenting the character-matrices to the mold, a rocking metal-pot, a series of pumps arranged for operation in said pot and having independent communication with the mold-cells, a nozzle-plate interposed between said mold and pot and having nozzles communicating with the mold-cells and said pumps, means for shifting the mold and nozzle-plate from casting position, means for stopping movement of the nozzle-plate before the mold has completed its movement and means for ejecting type from the mold and nibs from the nozzle plate.

13. The combination with a mold having mold-cells adapted for casting individual type, of a series of matrix-bars having character-matrices, means for presenting a character-matrix to the mold, a rocking metal-pot, a series of pumps arranged for operation therein and having independent com-

- 5 munication with the mold-cells, means connecting said pot and mold whereby the former moves the mold away from the matrix-bar to disengage the cast type from the character matrix, means for shifting the mold to ejecting position and means for ejecting the type therefrom.
- 10 14. The combination with a mold having mold-cells adapted for casting individual type, of a series of matrix-bars having character-matrices, means for presenting a character matrix to the mold, a rocking metal-pot, a series of pumps arranged for operation therein and having independent 15 communication with the mold cells, a nozzle-plate interposed between said mold and pot and having nozzles communicating with the mold-cells and said pumps, means connecting the mold and the metal-pot whereby the former is withdrawn by the latter to disengage the cast type from the character-matrix, means for shifting the mold and nozzle-plate from casting position, means for stopping the movement of said 20 nozzle plate before the mold has completed its movement, and means for ejecting type from the mold and nibs from the nozzle-plate.
- 25 15. The combination with a mold having mold-cells adapted for casting individual type, of a series of matrix-bars having character-matrices, means for presenting a character-matrix to the mold, a matrix-lifter, means connecting said matrix-lifter with the mold, means for injecting metal into the mold, means for shifting the mold from casting to ejecting position during which the matrix-bars are restored to initial position by the matrix-lifter, means for releasing the matrix-bar lifter from the mold when the matrices have been restored, and means for ejecting type from the mold.
- 30 16. The combination with a mold having mold-cells adapted for casting individual type, of a series of matrix-bars having character-matrices, means for presenting a character-matrix to the mold, means for injecting metal into the mold, means for shifting the mold from casting to ejecting position, means for ejecting type from the mold, and a type-transferring screw into the grooves of which the type are entered by the ejecting mechanism.
- 35 17. The combination with a mold having mold-cells adapted for casting individual type, of a series of matrix-bars having character-matrices, means for presenting a character-matrix to the mold, means for injecting type into the mold-cells, means for shifting the mold from casting to type-ejecting position, means for ejecting type from the mold, and a screw-conveyer having grooves of different width which grooves receive the type ejected from the mold and transfer and 40 compose the same in a stick.
- 45 18. The combination with a mold having mold-cells adapted for casting individual type, of a series of matrix-bars having character-matrices, means for presenting a character-matrix to the mold, means for injecting type into the mold-cells, means for shifting the mold from casting to type-ejecting position, means for ejecting type from the mold, a screw-conveyer having grooves which receive the type ejected from the mold and transfer and compose the same into a stick, and means for intermittently rotating said conveyer. 70
- 50 19. The combination with a mold having mold-cells adapted for casting individual type, of a series of matrix-bars having character-matrices, means for presenting a character-matrix to the mold, means for injecting type into the mold-cells, means for shifting the mold from casting to type-ejecting position, means for ejecting type from the mold, a screw-conveyer having grooves of different width which receive the type ejected from the mold and transfer and compose the same into a stick, and means for intermittently rotating said conveyer. 80
- 55 20. The combination with a mold having mold-cells adapted for casting individual type, of a series of matrix-bars having character-matrices, means for presenting a character-matrix to the mold, means for injecting type into the mold-cells, means for shifting the mold from casting to type-ejecting position, type-ejecting mechanism, a screw into the grooves of which the type are received, means for rotating said screw, and means for stopping the rotation of the screw during the type-ejecting operation. 90
- 60 21. The combination with a mold having mold-cells adapted for casting individual type, of a series of matrix-bars having character-matrices, means for presenting a character-matrix to the mold, means for injecting type into the mold-cells, means for shifting the mold from casting to type-ejecting position, type-ejecting mechanism, a screw into the grooves of which the type are received, means for rotating said screw, and means operated by the movement of the mold for stopping the rotation of the screw during the type-ejecting operation. 100
- 65 22. In a type-casting machine, the combination with a mold for casting individual type, of means for injecting metal into said mold against a character-matrix, means for shifting the mold from casting to ejecting position, a screw-conveyer the grooves of which receive the type ejected from the mold, means for rotating said screw, and means engaging the screw for stopping rotation thereof during the operation of entering the type thereinto. 110
- 70 23. In a type-casting machine, the combination with a mold for casting individual type, of means for injecting metal into said 120
- 75 130

- mold against a character-matrix, means for shifting the mold from casting to ejecting position, a screw-conveyer the grooves of which receive the type ejected from the 5 mold, means for rotating said screw, and means operated by the mold for engaging the screw and stopping rotation thereof during the operation of entering the type thereinto.
- 10 24. In a type-casting machine, the combination with a mold for casting individual type, of means for injecting metal thereinto against a character-matrix, means for shifting the mold from casting to ejecting position, a type-rail onto which the type are ejected, a screw the grooves of which receive said type, means for rotating the screw, a guard for preventing escape of the type from the screw, and automatic means for bringing said guard into and out 75 of operation.
- 15 25. The combination with a mold for casting individual type, of means for injecting metal thereinto against a character-matrix, means for shifting the mold from casting to ejecting position, a type-rail onto which the type are ejected, a screw the grooves of which receive the type, a guard for preventing escape of the type from the screw, and means operated by the mold for bringing 80 the guard into and out of operation.
- 20 26. The combination with a mold for casting individual type, of means for injecting metal thereinto against a character-matrix, means for shifting the mold from casting to ejecting position, a type-rail onto which the type are ejected, a screw the grooves of which receive said type, means for rotating said screw, a guard for preventing the escape of type from the screw, means for 85 preventing rotation of the screw at intervals operating synchronously with the guard and arranged to stop rotation of the screw when the guard is out of operation, and automatic means for actuating said guard and locking 90 means.
- 25 27. The combination with a mold for casting individual type, of means for injecting metal thereinto against a character-matrix, means for shifting the mold from casting to ejecting position, a type-rail onto which the type are ejected, a screw the grooves of which receive said type, means for rotating said screw, a guard for preventing the escape of type from the screw, means for preventing rotation of the screw at intervals operating synchronously with the guard and arranged to stop rotation of the screw when the guard is out of operation, and means operated by the mold for actuating said 95 guard and locking means.
- 30 28. The combination with a mold for casting individual type, of means for injecting metal thereinto against a character-matrix, means for shifting the mold from casting to ejecting position, a type-rail onto which the type are ejected, a screw the grooves of which receive said type, means for rotating the screw, a guard for preventing escape of the type from the screw, means carried by said guard for intermittently locking said screw from rotation when the guard is out of operation, and means for automatically bringing 100 said guard into and out of operative position.
- 35 29. The combination with a mold for casting individual type, of means for injecting metal thereinto against a character-matrix, means for shifting the mold from casting to ejecting position, a type-rail onto which the type are ejected, a screw the grooves of which receive said type, means for rotating the screw, a guard for preventing escape of the type from the screw, means carried by said guard for intermittently locking said screw from rotation when the guard is out of operation, and means operated by the mold for automatically bringing 105 said guard into and out of operative position.
- 40 30. The combination with a mold for casting individual type, of means for injecting metal thereinto against a character-matrix, means for shifting the mold from casting to ejecting position, a type-rail onto which the type are ejected, a screw-conveyer, means for rotating said screw, a guard for preventing escape of the type from the screw, means carried by said guard for intermittently locking the screw from rotation when the guard is out of operation, a lever operatively engaged at one end with said guard, and means carried by the mold for engaging said lever to bring said guard into and out of operative position.
- 45 31. The combination with a mold for casting individual type, of means for injecting metal thereinto against a character-matrix, a type-rail, means for ejecting type from the mold onto said rail, a stick, and a screw-conveyer for transferring said type to, and composing the same in said stick.
- 50 32. The combination with a mold for casting individual type, of means for injecting metal thereinto against a character-matrix, a type-rail, means for ejecting type from the mold onto said rail, a stick, a screw-conveyer for transferring said type to and composing the same in said stick, and a guard for preventing escape of type from the screw.
- 55 33. The combination with a mold for casting individual type, of means for injecting type thereinto against a character-matrix, a type-rail, means for ejecting type from the mold onto said rail, a stick, a screw-conveyer for transferring said type to and composing the same in said stick, a guard for preventing the escape of type from the screw, and means for automatically bringing said guard into and out of operation.
- 60 34. The combination with a mold for casting individual type, of means for injecting

- metal thereinto against a character-matrix, a type-rail, means for ejecting type from the mold onto said rail, a stick, a screw-conveyer for transferring said type to and composing the same in said stick, a guard for preventing escape of type from the screw, and means for locking the screw from rotation during the type-ejecting operation.
35. The combination with a mold for casting individual type, of means for injecting metal thereinto against a character matrix, a type-rail, means for ejecting type from the mold onto said rail, a stick, a screw-conveyer for transferring said type to and composing the same in said stick, a guard for preventing escape of type from the screw, and means for automatically locking the screw from rotation during the type-ejecting operation.
36. The combination with a mold for casting individual type, of means for injecting metal thereinto against a character-matrix, a type-rail, means for ejecting type from the mold onto said rail, a stick, a screw-conveyer for transferring said type to and composing the same in said stick, a guard for preventing escape of type from the screw, and means for preventing rotation of the screw at intervals operating synchronously with the guard and arranged to stop rotation of the screw when the guard is out of operation.
37. The combination with a mold for casting individual type, of means for injecting metal thereinto against a character-matrix, a type-rail, means for ejecting type from the mold onto said rail, a stick, a screw-conveyer for transferring said type to and composing the same in said stick, a guard for preventing escape of the type from the screw, means carried by said guard for intermittently locking the screw from rotation when the guard is out of operation, and means for automatically bringing said guard into and out of operation.
38. The combination with a mold for casting individual type, of means for injecting metal thereinto against a character-matrix, a type-rail, means for ejecting type from the mold onto said rail, a stick, a screw-conveyer for transferring said type to and composing same in said stick, a guard for preventing escape of the type from the screw, means carried by said guard for intermittently locking the screw from rotation when the guard is out of operation, and means carried by the mold for automatically bringing said guard into and out of operation.
39. The combination with a mold adapted for casting individual type, of means for injecting metal into said mold against a character-matrix, a type-rail, means for ejecting type from the mold onto said rail, a stick comprising a movable element having an extension with an indicator working in front of a scale, and means for transferring the type into and composing it in said stick, substantially as described.
40. The combination with a mold adapted for casting individual type, of means for injecting metal into said mold against a character-matrix, a type-rail, means for ejecting type from the mold onto said rail, a stick comprising a movable element having an extension with an indicator working in front of the scale, and a screw-conveyer for transferring the type into and composing it in said stick, substantially as described.
41. The combination with a mold having cells adapted for casting individual type, of means for injecting metal into said mold against a character-matrix, a type-rail, means for ejecting type from the mold onto said rail, a stick, a galley, an element movably arranged in said stick and acted upon by the type during the process of composition, line-ejecting mechanism for transferring the composed lines of type from the stick to the galley, and means actuated by the movable element of the stick for operating the line-ejector.
42. The combination with a mold having cells adapted for casting individual type, of means for injecting metal into said mold against a character-matrix, a type-rail, means for ejecting type from the mold onto said rail, a stick, a galley, a movable element having an extension provided with an indicator working in front of a scale arranged in said stick and acted upon by the type during the process of composition, line-ejecting mechanism for transferring the composed lines of type from the stick to the galley, and means actuated by the movable element of the stick for operating the line-ejector.
43. The combination with a mold having cells adapted for casting individual type, of means for injecting metal into said mold against a character-matrix, a type-rail, means for ejecting type from the mold onto said rail, a stick, a galley, a lead magazine, and mechanism for transferring a composed line of type from the stick to the galley and superimposing thereon a lead.
44. The combination with a mold having cells adapted for casting individual type, of means for injecting metal into said mold against a character-matrix, a type-rail, means for ejecting type from the mold onto said rail, a stick, a galley, a lead magazine, mechanism for transferring a composed line of type from the stick to the galley and superimposing thereon a lead, and intermittently-operated means for moving the galley into proper position to receive a line of type.
45. The combination with a mold adapted for casting type, of means for injecting metal into said mold against a character-matrix, means for ejecting type from said

- 5 mold, a stick, means for transferring the type to and composing it in said stick, a screw, a galley mounted on said screw, means for transferring a composed line of type 5 from the stick to the galley, and means for rotating said screw to adjust the position of the galley.
- 10 46. The combination with a mold adapted for casting type, of means for injecting metal into said mold against a character-matrix, means for ejecting type from said mold, a stick, means for transferring the type to and composing it in said stick, a screw, a galley mounted on said screw, means 15 for transferring a composed line of type from the stick to the galley, and means moving in unison with the line-transferring mechanism for rotating said screw to adjust the position of the galley.
- 20 47. The combination with a mold adapted for casting type, of means for injecting metal into said mold against a character-matrix, means for ejecting type from said mold, a stick, means for transferring the type to and composing it in said stick, a screw, a galley mounted on said screw, means 25 for transferring a composed line of type from the stick to the galley, and adjustable means for rotating said screw to adjust the 30 position of the galley.
48. The combination with a mold adapted for casting type, of means for injecting metal into said mold against a character-matrix, means for ejecting type from said mold, a stick, a galley, means for transferring type to and composing the same in said stick, a line transerrer, and devices controlled by the line of type for connecting the line-ejector and type-ejector whereby 40 the former is actuated by the latter for transferring a composed line of type from the stick to the galley.
49. The combination with a mold adapted for casting type, of means for injecting metal into the mold against a character-matrix, ejecting mechanism for ejecting type from the mold, a stick, means for transferring type to and composing the same in said stick, a screw, a galley mounted on 50 said screw, a line-ejector, ratchet mechanism operatively arranged in connection with said screw, and a rack actuated by the line-ejector for rotating said screw and positioning the galley with relation to the stick.
- 55 50. The combination with a mold adapted for casting type, of means for injecting metal into the mold against a character-matrix, ejecting mechanism for ejecting type from the mold, a stick, means for transferring type to and composing the same in said stick, a screw, a galley mounted on said screw, a line-ejector, ratchet mechanism operatively arranged in connection with said screw and an adjustable rack actuated by 60 the line-ejector for rotating said screw and 65 positioning the galley with relation to the stick.
51. The combination of a composing stick, a screw, a galley adjustably mounted on said screw, means for transferring a composed line of type from the stick to the galley, and means for rotating the screw to position the galley to receive said line of type.
52. The combination of a composing stick, galley-adjusting screw, a galley detachably connected with said screw, means for transferring a composed line of type from the stick to the galley, and means for rotating the screw to position the galley to receive 70 said line of type.
53. The combination with a mold having cells adapted for casting individual type, of means for selectively presenting character-matrices in front of the mold-cells, means for injecting metal into the cells of said 80 mold, means for ejecting type from said mold, a screw-conveyer the grooves of which receive the type, and a stick into which the type are transferred by said screw.
54. The combination with a mold having cells adapted for casting individual type, of means for selectively presenting character-matrices in front of the mold-cells, a metal-pot, a series of pumps operating in said pot and having independent communication with 90 the cells of the mold for injecting metal thereinto, means for ejecting type from the mold, a screw-conveyer the grooves of which receive the ejected type, and a stick into which the type are conveyed by the 95 screw.
55. The combination with a mold having cells adapted for casting individual type, of means for selectively presenting character-matrices in front of the mold-cells, a metal-pot, a series of pumps operating in said pot and having independent communication with 100 the cells of the mold for injecting metal thereinto, means for preventing the operation of part of said pumps and permitting 105 operation of the remainder thereof, means for ejecting type from the mold, a screw-conveyer the grooves of which receive the ejected type, and a stick into which the type are conveyed by the screw.
56. The combination with a mold having cells adapted for casting individual type, of a metal-pot, a series of pumps operating in said pot and having independent communication with the mold-cells, a series of matrix-bars having character-matrices, means for selectively presenting the matrices to the mold, means governed by the matrix-bars for locking part of said pumps from operation and permitting operation of the remainder thereof, means for ejecting type from the mold, a screw-conveyer the grooves of which receive the ejected type, and a stick into which the type are conveyed by the 110 screw.
57. The combination with a mold having cells adapted for casting individual type, of a metal-pot, a series of pumps operating in said pot and having independent communication with the mold-cells, a series of matrix-bars having character-matrices, means for selectively presenting the matrices to the mold, means governed by the matrix-bars for locking part of said pumps from operation and permitting operation of the remainder thereof, means for ejecting type from the mold, a screw-conveyer the grooves of which receive the ejected type, and a stick into which the type are conveyed by the 115 screw.
58. The combination with a mold having cells adapted for casting individual type, of a metal-pot, a series of pumps operating in said pot and having independent communication with the mold-cells, a series of matrix-bars having character-matrices, means for selectively presenting the matrices to the mold, means governed by the matrix-bars for locking part of said pumps from operation and permitting operation of the remainder thereof, means for ejecting type from the mold, a screw-conveyer the grooves of which receive the ejected type, and a stick into which the type are conveyed by the 120 screw.
59. The combination with a mold having cells adapted for casting individual type, of a metal-pot, a series of pumps operating in said pot and having independent communication with the mold-cells, a series of matrix-bars having character-matrices, means for selectively presenting the matrices to the mold, means governed by the matrix-bars for locking part of said pumps from operation and permitting operation of the remainder thereof, means for ejecting type from the mold, a screw-conveyer the grooves of which receive the ejected type, and a stick into which the type are conveyed by the 125 screw.
60. The combination with a mold having cells adapted for casting individual type, of a metal-pot, a series of pumps operating in said pot and having independent communication with the mold-cells, a series of matrix-bars having character-matrices, means for selectively presenting the matrices to the mold, means governed by the matrix-bars for locking part of said pumps from operation and permitting operation of the remainder thereof, means for ejecting type from the mold, a screw-conveyer the grooves of which receive the ejected type, and a stick into which the type are conveyed by the 130 screw.

57. The combination with a mold having cells adapted for casting individual type, of a metal-pot, a series of pumps arranged to operate in said pot and having independent communication with the mold-cells, a series of matrix-bars having character matrices, means for selectively presenting said matrices to said mold, bolts for engaging the pump-elements, the co-operative relation between said matrix-bars, pump-elements and bolts being such that when the matrix bars are in initial, or stored, position the pumps are locked from operation, and when the matrix-bars are in type-casting position the pumps are permitted to operate, means for ejecting type from the mold, a screw-conveyer the grooves of which receive the ejected type, and a stick into which the type are conveyed by the screw.
- 10 58. The combination with a mold having cells adapted for casting individual type, of a metal-pot, a series of pumps arranged to operate in said pot and having independent communication with the mold-cells, a key mechanism and intermediate mechanism for selectively presenting a matrix-character to a mold-cell and permitting operation of the corresponding pump, means for ejecting type from the mold, a screw-conveyer the grooves of which receive the ejected type, and a stick into which the type are conveyed by the screw.
- 15 59. A mold for casting type, comprising a bed-piece, a series of sections of hardened material fitted upon said bed-piece and constituting the side walls of the mold-cells, a series of cell-bottom pieces alternately arranged with said sections and constituting the bottoms of the mold-cells, and means for maintaining the inter-relation of the said bed, sections and pieces.
- 20 60. A mold for casting type, comprising a bed-piece, a series of sections of hardened material fitted upon said bed-piece and constituting the side walls of the mold-cells, a series of cell-bottom pieces alternately arranged with said sections and constituting the bottoms of the mold-cells, an upper bed, a series of sections of hardened material fitted thereto and constituting the top walls of the mold-cells, and means for maintaining the inter-relation of said bed, sections and pieces.
- 25 61. In a machine for casting individual type, a mold comprising a bed-piece, a series of sections of hardened material fitted upon said bed-piece and constituting the side walls of the mold-cells, a series of cell-bottom pieces alternately arranged with said sec-
- tions and constituting the bottoms of the mold-cells, an upper bed, a series of sections of hardened material fitted thereto and constituting the top walls of the mold-cells, means for maintaining the inter-relation of said beds, sections and pieces, and means for incorporating said mold into the mechanism.
- 30 62. In a machine for casting type, the combination with a mold, of a series of matrix-bars provided with character-matrices, means for selectively presenting the character-matrices of said bars to the mold, means for shifting the mold from casting to ejecting position, a matrix-lifter and means carried by the mold for engaging said lifter to return the matrix bars to initial position.
- 35 63. In a machine for casting type, the combination with a mold, of a series of matrix bars provided with character-matrices, means for selectively presenting the character-matrices of said bars to the mold, means for shifting the mold from casting position to ejecting position, a matrix-lifter, and pivoted fingers carried by the mold adapted to engage said lifter to return the matrix bars to initial position.
- 40 64. In a machine for casting type, the combination with a mold, of a series of matrix bars provided with character-matrices, means for selectively presenting the character-matrices of said bars to the mold, means for shifting the mold from casting to ejecting position, a matrix-lifter, pivoted fingers carried by the mold and adapted to engage said lifter to return the matrix-bars to initial position, and means for automatically releasing said fingers from said matrix-lifter.
- 45 65. In a machine for casting type, the combination with a mold, having a series of cells adapted for casting individual type, a series of matrix-bars having character matrices, means for selectively presenting the character-matrices to the mold, a rocking metal-pot, means for ejecting metal from said pot into said mold-cells, means for shifting the mold from casting to ejecting position and a wiper carried by the mold and operating to sweep across the face of the pot and keep the same clear and clean.
- 50 In testimony whereof I have hereunto set my hand in presence of two subscribing witnesses.
- 55

JOSEPH C. FOWLER.
